[57] CLAIM

The ornamental design for a toy loader, substantially as shown and described.

DESCRIPTION

FIG. 1 is a front perspective view of a toy loader showing my new design;

FIG. 2 is a right-side elevational view thereof shown on an enlarged scale;

FIG. 3 is a front elevational view thereof;

FIG. 4 is a rear elevational view thereof;

FIG. 5 is a top plan view thereof; and

FIG. 6 is a right-side elevational view with the bucket in lowered position.

The tire lugs fragmentarily shown in FIG. 1 are continuous over the surface of the tire members.

FIG. 1**FIG. 2**

FIG. 3**FIG. 4**

FIG. 5**FIG. 6**
